J. P. TIRRELL, OF NORTH BRIDGEWATER, MASSACHUSETTS, ASSIGNOR TO HIMSELF AND J. O. NASH, J. E. NASH, AND IRA MERRITT.

Letters Patent No. 63,442, dated April 2, 1867.

IMPROVED MACHINE FOR FORMING THE BARS OF CROCHETING AND KNITTING NEEDLES.

The Schedule referred to in these Letters Patent and making part of the same.

TO ALL WHOM IT MAY CONCERN:

Be it known that I, J. P. TIRRELL, of North Bridgewater, of Plymouth county, in the State of Massachusetts, have invented a new and useful Machine for Cutting Crochet Needles and other similarly-shaped instruments; and I do hereby declare that the following is a full and exact description thereof, reference being had to the accompanying drawings, making part of this specification.

My invention has for its object to produce an organized machine to perform the entire operation of cutting the grooved and barbed portion of crochet needles and other similarly-shaped instruments. Previous to my invention it has been customary in the manufacture of barbed needles (such, for instance, as used in crocheting and in knitting machinery) to take the needles or needle blanks, after being pointed, and cut out the grooves on either side, and cut away the stock, so as to form the hook or barb by hand. I have conceived and put into operation an organized mechanism, which performs this entire operation on the needle blank mechanically with greater rapidity, and at the same time with greater precision and in a more desirable manner, than has been or can be done by hand tools and hand manipulation.

My invention consists in an organized mechanism, in which the needle blank is held upon a compound carriage, which carries it along longitudinally a certain distance, then rotates it (in a horizontal plane) and then traverses onward again, while a rotatory cutter performs the cutting operations; all as hereinafter fully described.

To enable those skilled in the art to make and use my invention, I will proceed to describe the construction and operation of one of my machines, referring by letters to the accompanying drawings, in which—

Figure 1 is a vertical sectional elevation.

Figure 2, a front view.

Figure 3, a partial top view; and

Figure 4, a diagram of the needle as cut by the machine illustrated in the preceding figures.

At fig. 2 I have represented the frame or stand in which the cutter-shaft is mounted, as if partially broken away, so as to illustrate more clearly the device for adjusting said shaft; and at fig. 3 I have illustrated the motions or variable positions of the needle-table in red lines.

In the several figures the same part is indicated by the same letter of reference.

G B is the base or bed of the machine, upon which are arranged two movable beds or carriages, E and A'; one of them, E, is a traversing carriage, and the other, A', has simply a motion for adjustment, and remains stationary during the operation of the machine. This latter is adjusted in its seat by means of a screw-shaft, f, working in its rear portion, and against a bar or stand, g, (see fig. 1,) and is provided with this means of adjustment for the purpose of changing the position of the cutter d e, the shaft a of which is mounted in suitable bearing-boxes on the arms A A of said carriage A'. The said shaft a is provided at its upper end with a suitable driving-pulley, c, by which a rotatory motion is imparted from any suitable motive power; and it is also provided with a means of longitudinal adjustment, which I will describe as follows: The shaft a is turned down at a point between its two bearings, and around this reduced portion is arranged an embracing box, b, in such manner that any movement of said box, in the direction of the length of the shaft, will cause a corresponding movement of the shaft itself, the latter being free to move longitudinally in its bearings or boxes. Through this box b passes also a screw-rod, q, (see fig. 2,) which takes bearings at either end against the adjacent sides of the two boxes of stands A A, and around one end of which is a small spring, r. Now, it will be seen that by turning the screw-shaft or rod q the box b will be moved in the direction of the length of shaft a, and since said shaft is locked longitudinally to said box, said shaft a, it will be seen, will be adjusted or moved longitudinally, just in proportion to the extent the screw-rod q is turned. Thus, by the adjustment (just described) of the shaft a in its boxes, and the adjustment of the carriage A', (as before explained,) it will be seen the position of the milling tool or cutter d e may be varied to adapt it precisely to the work on the table to be operated upon. The carriage E has a reciprocating motion, and is carried back and forth by means of a screw-shaft, u, working in said carriage, and having a fixed bearing in a stand, v, fast on the base G, (see figs. 2 and 3.) Said screw-shaft u is represented as having a crank-handle, w, by means of which the operator of the machine turns it to

effect the motions of the carriage E. On this carriage is arranged a swinging or vibratory table D, (which, in connection with said carriage, may be said to constitute a compound carriage, as alluded to in describing the nature of my invention,) which is free to swing or vibrate in a horizontal plane, around a screw-stud or pivot, h, (see fig. 1,) and on which is arranged an adjustable work stock or needle holder, in which the needle blank is clamped while undergoing the cutting operation. This work stock or clamp is composed of a bed-piece, k, (which may be adjusted on table D by means of set-screws i i;) and a clamping-plate, m, which is pivoted at p, and forced and held down, at the will of the operator, by means of a sliding gripping-bar, l, which is arranged to slide over and hold down the free end of the bar m, and which is provided with a suitable handle to operate it with. By means of this clamping stock, the needle blank is securely held in position, as seen at figs. 1 and 3, while the cutting operations are performed on it. y is a vibrating spring gauge, which is free to turn on its pivot, and held up toward the side of carriage E by means of its spring z, (see figs. 3 and 2.) This gauge pawl, y, operates to hold the pin d', which protrudes from the end of swinging table D, and regulates the motions of the latter, as will be presently described.

Having so far explained the construction and arrangement of the several parts, the following general description of the operation of the whole machine will suffice to give a full and correct understanding of my invention: The needle blank being clamped in position, (in the manner before explained,) as seen at fig. 3, the table E is driven along in the direction indicated by the arrow, which causes the needle blank to come in contact with the mill or cutter d e, the latter commencing to cut nearest the point of the blank H, and cutting the groove along the side of the blank. By the time the pin d' has reached the end of the vertically projecting lip of gauge-plate y, the groove will have been cut sufficiently far along on the side of the needle, and the pin d' then being released from the lip or flanch of plate y, the operator takes hold of the end of swinging table D, and vibrating it, in the direction indicated by the red lines at fig. 3, causes the needle blank to swing around beneath the constantly-rotating cutter d e, and receive the cut to form the barb, and when the table D has been moved around a half circle, the reciprocatory motion of table E is then continued, in the direction of the arrow, and the groove on the other side of the needle finished out to the point, and so on the operation of the machine is continued. The mill or tool d e must of course be made of the proper shape and size to cut the grooves of the proper shape, and all the needles will require will be perhaps a little friction to present them in a perfectly finished condition. I have explained the table D as being swung around by hand, as this is the simple method employed in the machinery which I have made and successfully worked, but it will be understood that the table D may be made to perform all its motions by automatic mechanism, if it be deemed expedient to so complicate the machine.

I do not desire to be limited to any of the precise devices or arrangement of mechanism in carrying out my invention, but having explained the construction and operation of my machine for cutting crochet needles and other similar instruments, what I claim as new, and desire to secure by Letters Patent, is—

The combination of devices, or their equivalents, substantially as described, by means of which the needle blank is held and carried and acted upon by the milling tool, all as set forth.

In testimony whereof I have hereunto set my hand and seal this day of June, 1866.
J. P. TIRRELL. [SEAL.]
